UNITED STATES PATENT OFFICE.

GEORGE E. McELROY, OF NEWARK, NEW JERSEY, ASSIGNOR TO McELROY ENGINE COMPANY, OF NEWARK, NEW JERSEY, A CORPORATION OF NEW JERSEY.

SILDE-VALVE.

1,206,121.

Specification of Letters Patent. Patented Nov. 28, 1916.

Application filed December 18, 1915. Serial No. 66,533.

To all whom it may concern:

Be it known that I, GEORGE E. McELROY, a citizen of the United States, residing at Newark, in the county of Essex and State 3 of New Jersey, have invented certain new and useful Improvements in Slide-Valves, of which the following is a specification.

My invention relates to improvements in internal combustion engines and particularly 10 to the type wherein inlet and exhaust ports in the cylinder wall are opened and closed by a slide valve.

The objects of my invention are the production of a simple and effective means for 15 holding the valve in a gas tight seat over the ports at all times without undue friction and regardless of heat conditions and to automatically take up any wear between the valve and seat.

20 In the drawing Figure 1 is a top view of my valve mechanism and Fig. 2 a side view, partly in section.

The cylinder 1 is provided with the customary water jacket 2 formed between the 25 cylinder wall 1 and the outer wall 3. The valve pocket 4 in the upper end of one side of the cylinder is provided with an inlet port 5 and an exhaust port 6.

The slide valve 7 fits up against the seat 30 4 and has the hole 10 drilled through it with the enlargements 11 and 12 at either end. The valve stem 13 is threaded at the upper end. A nut 14 at the lower end supports a sleeve 15 which is less in diameter than 35 the opening 10 and a trifle longer so that when the nut 16 is screwed down onto the sleeve 15 the valve 7 will not bind on the stem but on the contrary will have a limited lateral movement. The valve stem 13 extends 40 downwardly through the casting and contacts with a cam 17 which reciprocates the valve. Opposite the valve seat the casting is made solid at 18 with the opening 19 therethrough threaded at the outer end. A 45 recess 20 in the valve receives one end of the pushrod 21, the other end of which engages the recessed end of a plug 22 in the hole 19. A spring 23 bears against the plug 22 and is in turn compressed by the 50 screw 24. The spring 23 acting through the plug 22 and push rod 21 presses the valve 7 into a gas tight seat with a firm but light pressure to avoid underfriction and wear and, by expansion and contraction, maintains 55 this pressure during reciprocation of

the valve in spite of the angular changes the rod 21 undergoes. The valve stem 13 being fixed in its position by its bearing in the casting but having a loose lateral connection with the valve in no wise restricts 60 or cramps the seating thrust of the spring and automatically enables the wear between the face of the valve and its seat to be taken up by the thrust of the spring. By moving the nuts 14 and 16 and the sleeve 15 up or 65 down the valve 7 may be accurately adjusted with respect to the ports 5 and 6. The valve 7 and push rod 21 are within the combustion space and are subject to the heat of explosion but the spring 23 is water jacketed 70 so that it is not unduly heated and its temper drawn. It is also apparent that the spring will automatically take up the expansion caused by heat in the valve, push rod and plug and will securely hold the 75] push rod in position in the sockets in the valve and plug.

The foregoing describes the mechanical form in which my invention has been embodied but the details may be varied to 80 meet different engine designs without departing from the scope of my invention.

I claim:-

1. In an internal combustion engine, a 85 valve pocket in the combustion space, a slide valve therein, a spring without the combustion space and means connecting said spring and valve for maintaining the valve in a gas tight seat in the pocket.

2. In an internal combustion engine, a 90 valve pocket in the combustion space, a slide valve therein, a push rod extending across the combustion space and bearing on the valve, a spring without the combustion chamber operating on the push rod to maintain a gas tight seat between the valve and its seat in the pocket.

3. In an internal combustion engine, a 95 valve pocket, a slide valve therein recessed in its outer face, a push rod one end of which engages said recess, an opening in the cylinder casting opposite the valve, a recessed plug therein engaging the other end of the push rod, a spring without the combustion space bearing on the plug and an 100 adjusting screw bearing on the spring.

4. In an internal combustion engine, a 105 valve pocket, a slide valve therein with an opening therethrough, a valve stem extending through the opening of less diameter 110

than the opening means on the stem holding the valve therebetween, and a pushrod one end of which bears on the valve and extends across the combustion space, a spring without the combustion space maintaining pressure on the other end of the rod for maintaining the valve in a gas tight seat in the pocket.

5. In an internal combustion engine, a valve pocket, a slide valve therein with an opening therethrough, a valve stem extending through the opening threaded at the upper end, a sleeve on the stem within the opening of less diameter and slightly greater

length than the opening, upper and lower nuts engaging the sleeve and valve, and a pushrod one end of which bears on the valve and extends across the combustion space, a spring without the combustion space maintaining pressure on the other end of the rod for maintaining the valve in a gas tight seat in the pocket.

In testimony whereof I have affixed my signature in presence of two witnesses.

GEORGE E. McELROY.
